Lacey & Lacey, Attorneys

UNITED STATES PATENT OFFICE.

JOHN C. BRITCHER, OF YORK, PENNSYLVANIA.

TURBINE.

Application filed May 1, 1923. Serial No. 635,950.

To all whom it may concern:

Be it known that I, JOHN C. BRITCHER, a citizen of the United States, residing at York, in the county of York and State of Pennsylvania, have invented certain new and useful Improvements in Turbines, of which the following is a specification.

This invention relates to hydraulic turbines and has for its object the provision of simple and efficient means for controlling the entrance of the water to the rotor. The invention seeks to provide means whereby the volume of water flowing to the rotor may be very accurately controlled, and also to provide means whereby the flow of water to the rotor may be entirely cut-off quickly in the event of accident, and a further object of the invention is to provide novel means for operating the wicket gates. These stated objects, and other objects which will incidentally appear in the course of the following description, are attained in such a mechanism as is illustrated in the accompanying drawings, and the invention resides in certain novel features which will be particularly pointed out in the claims following the description.

In the drawings:

Figure 1 is a side elevation of one embodiment of my invention, the outer casing or housing being shown in section;

Fig. 2 is a horizontal section on a larger scale;

Fig. 3 is a detail vertical section on the line 3—3 of Fig. 2;

Fig. 4 is a detail view showing one of the wicket gates and the operating arm therefor in perspective and disassembled.

The outer casing 1 may be of any desired form and dimensions and supported in any convenient or preferred manner, being provided at a proper point with an inlet 2 through which the water is admitted, and this inlet is, in actual practice, equipped with a cut-off valve in the usual manner. In the drawings, the turbine is shown disposed about a vertical axis but it may, of course, be set in other positions and will operate efficiently. The turbine comprises an upper housing 3 having a head 4 secured thereon and a lower housing 5 extending through the bottom of the casing 1 and communicat-

ing directly with an outlet pipe 6 whereby the waste or used water may be carried to any point of discharge. The lower housing 5 is provided with an annular flange 7 at its upper end which rests upon the bottom of the casing 1 and thereby supports the housing in position, and a ring 8 is secured upon the said flange 7 to mate with a ring 9 which is secured to the lower end of the housing 3. Between the said rings 8 and 9, the wicket gates 10 are pivotally mounted, and the said gates extend in an annular series around the entire turbine. The power shaft 11 extends through the head 4 of the upper housing 3 and any preferred form of boxing 12 is provided upon the said head for the shaft, as will be readily understood, a similar packing box or gland 13 being provided on the cover 14 of the main casing 1, as shown. The lower end of the power shaft 11 may be supported in any convenient manner in the lower housing 5 at any preferred point of the same, and blades or pockets 15 are secured to the power shaft so as to be acted upon directly by the water flowing through the space between the rings 8 and 9 in the usual manner. Fitted slidably through the upper ring 9 and the upper housing 3 is a cylinder gate 16 which has its lower edge arranged to rest upon the lower ring 8, as clearly shown in Fig. 3, whereby to entirely cut off the flow of water to the rotor blades or pockets, as will be readily understood. The outer circumferential surface of the cylinder gate bears against and rides over the inner circumference of the ring 9 so as to be guided thereby, and one or more rods 17 are fixed to and rise from the upper edge of the said gate to slide through the head 4 so that by raising and lowering the said rods the gate may be opened or closed. To effect movement of the said rods 17, a lever 18 is fulcrumed upon a suitable post 19 erected upon the head 4 and having pin and slot engagement with the upper ends of the rods 17, as shown at 20. A lifting bar or handle member 21 is pivoted to the opposite end of the lever 18 and rises through the cover 14 of the casing 1, as shown in Fig. 1, so that the lever may be actuated from any point within the building within which the turbine is located. A

latch plate 22 is illustrated to maintain the handle member 21 in a set position, and it is to be understood that this latch member may be of any desired or preferred form, 5 and that it may be mounted upon a packing box through which the lifting bar passes.

The wicket gates 10 each consists of a body, the upper and lower ends of which are substantially triangular, the apex of the 10 triangle or the point 23 of the gate being disposed at the inner end thereof. The gates are pivotally mounted between the rings 8 and 9 upon pivot bolts 24 extending through the respective gates between the ends thereof 15 of and serving to maintain the rings 8 and 9 in spaced relation, as will be readily understood upon reference to Fig. 3. It will be noted that the bolts 24 are threaded into the upper ring 9, as at 25, and are provided near 20 their lower ends with shoulders 45 abutting the ring 8 so that the bolts constitute supports for the rings as well as spacers to maintain the set relation of the same. The gates 10 are constructed in their lower portions with longitudinally extending sockets 26 which open through the outer wider ends of the gates and slidably receive operating arms 27 which are pivotally mounted at their outer ends upon a shifting ring 28. 25 A convenient mounting for the operating arms 27 is a knuckle consisting of a vertical sleeve 29 and a lateral sleeve 30 projecting from the sleeve 29 between the ends of the same. The end of the arm 27 is secured 30 in the sleeve 30 and a pivot screw 31 is inserted through the sleeve 29 into the shifting ring 28 whereby to pivotally attach the knuckle to the ring, as will be readily understood. The shifting ring 28 is fitted to 35 the outer circumference of the ring 8 by a tongue and groove structure, shown at 32, so that the shifting ring will be supported by the ring 8 and will extend entirely around the circumference thereof but may slide relatively thereto. The shifting ring is preferably constructed of two similar members provided at their ends with mating depending lugs 33 through which securing bolts 34 are inserted to secure the shifting ring in 40 place about the lower ring 8. At convenient points of the ring 28, I pivot thereto links 35 which extend outwardly therefrom and have their outer ends pivoted to a disk or collar 36 secured to a vertical adjusting 45 shaft or rod 37 which extends through the cover 14 of the casing 1 and is equipped with a handle 38 of any preferred form. A bearing 39 may be provided for the said rod or shaft 37 carried by a bracket 40 projecting from the upper housing 3, as shown in Fig. 1.

In Fig. 2 of the drawings, the cylinder gate 16 is shown in a partly closed position while the wicket gates 10 are shown in 50 fully opened position. The flow of water

may be entirely cut off by lowering the cylinder gate 16 or by rotating the shaft 37 to the right of Fig. 2, thereby causing the ends of the links 35 to move upwardly in the said figure and, consequently, turn the shifting ring 28 about the ring 8 in a direction contrary to the direction of movement of the shaft 37. The outer ends of the several arms 27 will, of course, follow the movement of the ring 28 and, 55 while they will slide outwardly relative to the several gates, they will also serve to turn the gates about their respective pivots 24 and, consequently, the inner tapered ends of the gates will be swung outwardly so that eventually they will come into contact with the inner face of the respectively adjacent gate thereby cutting off the flow of water. It will thus be seen that by providing the cylinder gate and a plurality of pivotally mounted wicket gates which are adapted to swing together in overlapping relation, I am enabled to very accurately regulate the volume of water admitted to the rotor of the turbine so that a conservation of the water 60 may be effected while all the power needed at any one time may be obtained through the rotation of the power shaft 11. Should one of the wicket gates be broken, it would, of course, be impossible to entirely cut-off the flow of water by merely shifting the wicket gates and in this emergency the cylinder gate is lowered into fully closed position so that the flow of water is cut-off and any water which may then enter the main casing 65 1 will be inert and will not impart any movement to the rotor. Of course, the flow through the inlet 2 will be cut-off as quickly as possible so that access to the broken wicket gate may be had and the necessary 70 repairs made. It may sometimes be desirable to set the wicket gates in fully opened position and adjust the cylinder gate into a partly closed position and, under some circumstances, it may be advantageous to maintain the cylinder gate in fully opened position and regulate the flow of water solely by the adjustment of the wicket gates but by providing both the cylinder gate and a plurality of wicket gates, I am enabled to 75 effect a greater and closer adjustment and regulation of the turbine than would be possible with either form of gate alone. The slidably mounted operating arms which control the wicket gates operate directly and quickly so as to shift the position of said gates when needed and respond readily to any movement of the shifting ring. The construction and arrangement of the parts are simple and open so that all the parts 80 are accessible when repairs are needed, but, due to the simplicity of the construction, the mechanism is not apt to get out of order and will operate efficiently for a long period without any attention. 85

Having thus described the invention, what is claimed as new is:

In a turbine, the combination of a rotor, a housing therefor including upper and lower rings spaced apart and defining an opening to admit fluid to the rotor, a plurality of wicket gates pivotally mounted between the said rings and provided with

longitudinal sockets opening through their outer ends, a shifting ring encircling the series of gates, and a plurality of arms slidably engaged in the sockets in the respective gates and having their outer ends pivotally connected with the shifting ring. ¹⁰

In testimony whereof I affix my signature.
JOHN C. BRITCHER. [L. s.]
